UNITED STATES PATENT OFFICE.

OTTO MADER, OF DESSAU, GERMANY, ASSIGNOR TO HUGO JUNKERS, OF DESSAU, GERMANY.

FUEL PUMP.

Application filed June 29, 1920. Serial No. 392,831.

To all whom it may concern:

Be it known that I, OTTO MADER, a citizen of the German Empire, residing at Dessau, Germany, have invented certain new and useful Improvements in Fuel Pumps (for which I have filed application in Germany, April 4, 1917, Patent No. 312,878; Austria, February 11, 1918; Hungary, February 28, 1918; Sweden, January 13, 1920; Norway, January 26, 1920; Denmark, January 28, 1920), of which the following is a specification.

My invention relates to fuel pumps for internal combustion engines and more especially to devices for simultaneously packing and lubricating the guides of moving parts of fuel pumps for internal combustion engines, which are intended to convey non-lubricating liquids, such as petrol or the like, which dissolve lubricants.

The use of such fuel pumps, which are to convey petrol and similar non-lubricating fluids, has hitherto been connected with considerable difficulty, which rendered a permanent and reliable operation of the pumps doubtful. This difficulty is mainly due to the fact that the lubricating oil conveyed to the gliding surfaces is dissolved by petrol and washed off, so that very soon the same conditions will occur as in a dry state, especially quick wear and tear and danger of sticking. Moreover, the slight surface-tension of petrol in the case of slight leakage of the guides will result in a considerable loss of liquid and irregularities in the supply, thereby causing great trouble in operating the engine. These difficulties will increase with the pressure, against which the pumps are intended to convey, and the more accurately the quantity of fuel to be supplied per stroke is to be measured. In view of these difficulties, fuel pumps for the dispersion and introduction of fuel immediately into the working cylinder for internal combustion engines have generally been abandoned, although by using pumps a far better dispersion, a more uniform composition of the mixture and a simpler regulation is ensured than with carburetters.

In accordance with the present invention, now, the drawbacks hitherto experienced with petrol pumps or the like are obviated by producing such a high and permanently uniform or rhythmically varying pressure in a space filled with lubricating fluid, in which

the guides of the moving part, which is to be packed and lubricated, ends at the side averted from the working space of the pump, that this mean pressure is higher than that of the non-lubricating fluid to be conveyed. In this operation, the lubricating fluid has the tendency to move in the guide or packing bar along the parts of the engine to the space containing the non-lubricating material. By this means, the guiding or packing track is continuously wetted with lubricating fluid and thus packed.

The quantity of lubricating oil entering the petrol or the like in such fuel pumps is so insignificant that it does not affect the further use of this fluid as a fuel and is of no importance from an economical point of view either.

In accordance with this invention the new arrangement may be so developed that the lubricating oil under pressure can be used not only for lubricating and packing the guides but also for moving such parts of the engine as are working in non-lubricating fluid, for instance pistons of pumps, valves or the like; furthermore for regulating this motion according to distance and time, for instance in the case of pumps for varying the quantity to be conveyed and the time of conveyance.

In the drawings affixed to this specification and forming part thereof different modifications of a fuel pump embodying my invention are illustrated by way of example. In the drawings

Figs. 1-4 are longitudinal sections of fuel pumps with stepped pistons.

Referring to the drawings, 1 is the casing of a pump, 2 the moved part of the engine, which works in non-lubricating fluid, for instance, the piston of a pump; 3 is the space filled with non-lubricating fluid; 4, is the pipe supplying such fluid; 5, is the suction-valve loaded with the spring 6; 7 is the pressure-valve with spring 8, and 9 the pressure-pipe of the pump; 12 is a crank-gear for driving a piston producing the pressure in the non-lubricating fluid. 14 is the space filled with lubricating fluid; 15 is a pipe for connecting the space 14 with a reservoir 16.

Figs. 1 to 4 show pumps, in which a pressure varying in harmony with the strokes of the pump is produced in the lubricating fluid by connecting the piston 2 of the pump with a step-piston 19. The step-

surface works in the annular space 14, which is filled with lubricating fluid.

- If, according to Fig. 1, the piston moves to the right, the lubricating fluid in the space 14 is conveyed through the overflow-valve 21 loaded with a spring 22, through the channel 20, thereby entering the reservoir 16 through the pipes 24 and 15, from which reservoir, after the return-motion of the piston into the left dead centre through the channel 15, it again fills up the annular space 14, whereupon the operation is gone through anew. To accelerate the process of filling, the annular space 14 may be provided with a suction-valve connected with the reservoir 16. The screw 23, which regulates the tension of the spring, serves for the adjustment of the pressure in the annular space 14.
- In order to ensure the pressure of the lubricating fluid in the space 14 during the conveying stroke to be higher, than that of the non-lubricating fluid in the space 3, the overflow-valve, which is constructed to form a piston 21, may be exposed to the pressure of both fluids through pipes 20, 25, as shown in Fig. 1. In that case, the spring 22 offers a certain excess safety for the pressure of the lubricating fluid. The piston 21 may be replaced by a diaphragm or the like.

Fig. 2 shows an arrangement similar to that shown in Fig. 1 with the modification that, in place of the loaded overflow-valve 21, a throttling screw 26 is used, which can be so regulated that the mean pressure of the lubricating fluid within the space 14 exceeds that of the non-lubricating fluid which is to be conveyed. This arrangement is to be recommended whenever the pump discharges the fluid through a mouth-piece (nozzle) 50, since, in that case, the pressures in the fluid to be conveyed as well as in the lubricating fluid bear almost the same proportion at all numbers of revolution, so that the screw 26 need not be readjusted for each number of revolutions.

In the modification of the pump without suction-valve as illustrated in the drawings the quantity to be conveyed may be easily regulated by displacing the dead centres of the piston 2.

Fig. 3 shows the same arrangement as Fig. 2, with the modification that the principle underlying the present invention of conveying lubricating fluid to the guides of such parts of the engine as are operating in non-lubricating fluid, is also applied to the pressure valve 7, which is here shown as being guided with a spindle 45 in a bore 27 of the piston 2. The space 27 is connected with the space 14 containing the lubricating fluid by means of the bore 28, so that the valve spindle guide is permanently lubricated. The pressure occurring in the non-lubricating fluid during the conveying

stroke assists in opening the pressure-valve 7.

As shown in Fig. 4, a positively controlled slide 30 is used in place of a pressure-valve, the guide of which is connected with the annular space 14 containing the lubricating fluid through the annular spaces 31, 32 and the channel 33, so that it is lubricated and tightened in the same manner as the guide of the piston 2.

It is obvious that the arrangement may be such that, by providing the slide 30 with steps and using special throttling screws, the slide itself will place under pressure the oil required for its own lubrication and packing.

In the place of step-pistons, special pistons, moved rhythmically and in unison with the piston of the pump (valves, slides), may be used, so as to produce a rhythmically varying pressure in the lubricating fluid.

I wish it to be understood that I do not desire to be limited to the exact details of construction shown and described, for obvious modifications will occur to a person skilled in the art.

I claim:

1. A liquid fuel pump comprising in combination, a pump cylinder, a piston in said cylinder, mechanical means for causing reciprocating motion of said piston in said cylinder and means for forcing lubricant under an average pressure exceeding the average pumping pressure in between the outer end of said piston and said cylinder.

2. A liquid fuel pump comprising in combination, a pump cylinder, a piston a portion of which projects from said cylinder, mechanical means for causing reciprocating motion of said piston in said cylinder, means for surrounding the portion of said piston which projects from said cylinder with lubricant and means for placing such lubricant under an average pressure exceeding the average pumping pressure.

3. A liquid fuel pump comprising in combination, a pump cylinder, a piston a portion of which projects from said cylinder, mechanical means for causing reciprocating motion of said piston in said cylinder, means for surrounding the portion of said piston, which projects from said cylinder, with lubricant and throttling means for placing such lubricant under an average pressure exceeding the average pumping pressure.

4. A liquid fuel pump comprising in combination, a stepped pump cylinder, a stepped piston, mechanical means for causing reciprocating motion of said piston in said cylinder, means for supplying liquid fuel into the narrow part of the cylinder, means for supplying lubricant into the wider part of said cylinder and means associated with said lubricant supplying means for creating in the wider part of said cylinder an aver-

age pressure exceeding the average pumping pressure.

5. A liquid fuel pump comprising in combination, a stepped pump cylinder, a stepped piston, mechanical means for causing reciprocating motion of said piston in said cylinder, means for supplying liquid fuel into the narrow part of said cylinder, means for supplying lubricant into the wider part 5 of said cylinder and an adjustable throttling means associated with said lubricant supplying means for creating in the wider part of said cylinder an average pressure exceeding the average pumping pressure.

15 6. A liquid fuel pump comprising in combination, a stepped pump cylinder, a stepped piston, mechanical means for causing reciprocating motion of said piston in said cylinder, means for supplying liquid fuel into the narrow part of said cylinder, a conduit comprising a plurality of branches for supplying lubricant into the wider part of said cylinder, one branch of said conduit leading to a point near the narrower part 20 of said cylinder, another branch to a point farther remote therefrom and a throttling means in the former branch for creating in the wider part of said cylinder an average pressure exceeding the average pumping 25 pressure.

30 7. A liquid fuel pump comprising in combination, a stepped pump cylinder, a stepped piston, mechanical means for causing reciprocating motion of said piston in said cylinder, means for supplying liquid fuel into the narrow part of said cylinder, a conduit comprising a plurality of branches for supplying lubricant into the wider part of said cylinder, one branch of said conduit leading 35 to a point near the narrower part of said cylinder, another branch to a point farther remote therefrom and a throttling means in the former branch for creating in the wider part of said cylinder an average pressure exceeding the average pumping pressure, said throttling means being arranged to be 40 acted upon also by the pumping pressure.

45 8. A liquid fuel pump comprising in combination, a stepped pump cylinder, a stepped

piston, mechanical means for causing reciprocating motion of said piston in said cylinder, means for supplying liquid fuel into the narrow part of said cylinder, a conduit for supplying lubricant into the wider part of said cylinder, one branch of said conduit comprising a plurality of branches leading to a point near the narrower part of said cylinder, another branch to a point farther remote therefrom and a loaded non-return valve in the first mentioned branch.

50 9. A liquid fuel pump comprising in combination, a stepped pump cylinder, a stepped piston, mechanical means for causing reciprocating motion of said piston in said cylinder, means for supplying liquid fuel into the narrow part of said cylinder, a conduit comprising a plurality of branches for supplying lubricant into the wider part of said cylinder, one branch of said conduit leading 55 to a point near the narrower part of said cylinder, another branch to a point farther remote therefrom, a loaded non-return valve in the first mentioned branch and a connection between the loaded side of said valve and the narrower part of said cylinder.

60 10. A liquid fuel pump comprising in combination, a stepped pump cylinder, a stepped piston, mechanical means for causing reciprocating motion of said piston in said cylinder, means for supplying liquid fuel into the narrow part of said cylinder, a conduit comprising a plurality of branches for supplying lubricant into the wider part of said cylinder, one branch of said conduit leading 65 to a point near the narrower part of said cylinder, another branch to a point farther remote therefrom, a valve inserted in said fuel supplying means and surrounded by an annular space, a connection between the former of said branches and said annular space and a throttling means in said former branch for creating in the wider part of said cylinder and in said space an average pressure exceeding the average 70 pumping pressure.

75 In testimony whereof I affix my signature.
OTTO MADER.
